UNITED STATES PATENT OFFICE

109,680

DESIGN FOR AN OVEN FRONT

Joseph V. Timmons, Dallas, Tex.

Application October 28, 1936, Serial No. 65,548

Term of patent 14 years

To all whom it may concern:

Be it known that I, Joseph V. Timmons, a citizen of the United States, residing at Dallas, in the county of Dallas and State of Texas, have invented a new, original, and ornamental Design for an Oven Front, of which the following is a specification, reference being had to the accompanying drawing, forming part thereof.

I claim:—

The ornamental design for an oven front as shown.

JOSEPH V. TIMMONS.
